PIERRE ZUCCO, OF SAN FRANCISCO, CALIFORNIA.

ADJUSTABLE FORM FOR CONCRETE ARCHES.

1,262,573.

Specification of Letters Patent.

Patented Apr. 9, 1918.

Application filed April 4, 1917. Serial No. 159,703.

To all whom it may concern:

Be it known that I, PIERRE ZUCCO, a citizen of the United States, residing at the city and county of San Francisco and State 5 of California, have invented new and useful Improvements in Adjustable Forms for Concrete Arches, of which the following is a specification.

This invention relates to forms for concrete arches, with particular reference to floor construction; and has for its object to provide a collapsible form which shall be quickly and easily adjustable to vary the 10 rise of the arch.

15 In the present invention I employ an arch form of any suitable material and shape which is removably held in place on the false-work, with the legs of adjacent arches embracing the horizontal support for the 20 abutment of the arch by means of novel and advantageous clamps. The arch forms and abutment supports are adjustable vertically relative to each other, whereby to vary the height of the abutments and thereby the 25 rise of the arch, and by reason of the arrangement of the arch forms extending outside of the abutment supports and detachably connected thereto, the said forms may be removed without disturbing the abutment supports and remaining false-work so 30 that said forms may be re-used before the concrete is set sufficiently to support itself.

In the accompanying drawings:

35 Figure 1 shows a transverse, sectional view of an arch embodying my invention.

Fig. 2 shows a longitudinal sectional view of the same.

40 Fig. 1 shows a horizontally extending abutment support 11 forming a part of the temporary support or false-work for the arch, running longitudinally of the forms and receiving and supporting the latter at their edges.

45 Embracing the abutment supports are arch forms 14 of any desired shape and character of material. Preferably they have their legs 15 made somewhat longer than usual and provided with a series of 50 perforations or apertures 16 to receive prongs 17 formed on the arms of clamps 18. The arch forms in reality receive their support entirely from the prongs in engagement with the abutment support and by 55 extending the prongs through other openings than those shown the legs and abut-

ment supports may be adjusted vertically relative to each other, whereby to vary the height of the arch.

The intermediate portion of each clamp 60 passes below the abutment support and has a transverse screw or rod 23 for drawing the arms together, whereby to hold the legs in engagement with the sides of the abutment support. The arms of the clamps provide relatively long supports which prevent the sides of the arches from bulging outwardly under the weight of the concrete.

65 The temporary supports or false-work (not shown) are first put in place with the 70 abutment supports 11 positioned at the required height and the arch forms are then put in place with their legs extending along the opposite sides of the abutment supports and held thereagainst by means of the 75 clamps 18 arranged at suitable intervals. By means of the prongs 17 the legs are positioned vertically according to the height of the arch desired. The concrete is poured into place and shortly thereafter the arch 80 forms may be removed, leaving the abutment supports in place, it being unnecessary to leave the arch forms in place until the concrete has become set sufficiently to support itself. For this reason a fewer number 85 of arch forms are made necessary in constructing a building.

Having thus described my invention, what I claim and desire to secure by Letters Patent is—

90 1. In a form for constructing concrete floors, an abutment support, an arch form having legs embracing opposite sides of the abutment support, and a clamp of substantially U-shape having prongs extending inwardly from the inner side faces of the arms of the clamp and formed so as to engage in perforations provided therefor in the legs of the arch form, the clamp being arranged so as to have its base extend below and across the abutment support and having a transverse rod member below said abutment support and engaged with intermediate parts of the arms of the clamp for drawing said arms together and against the opposite faces 95 of the arch form legs.

100 2. In a form for constructing concrete floors, an abutment support, an arch form having legs embracing opposite sides of the abutment support, a clamp of substantially U-shape having arms which embrace opposite side faces of the legs of the arch form 105 110

so as to provide relatively long supports for said legs preventing bulging thereof, said clamp having means engaging the abutment support to hold the form against down movement, and means engaged with intermediate parts of the clamp arms and extending thereacross to draw same together.

3. In a form for constructing concrete floors, an abutment support, an arch form having legs embracing opposite sides of the abutment support, a clamp of substantially U-shape having arms which embrace opposite side faces of the legs of the arch form so as to provide relatively long supports for said legs preventing bulging thereof, said clamp including means engaged with intermediate parts of the clamp arms and extending thereacross to draw same together, and means on the arms to extend through perforations provided therefor in the arch form

legs and engage the abutment support to hold said form against vertical movement.

4. In a form for constructing concrete floors, an abutment support, an arch form having legs embracing opposite sides of the abutment support, and a clamp having parts embracing opposite sides of the arch form with means to draw the clamp parts together, said clamp also having means extending transversely to the sides of the arch form legs and engaging the abutment support to hold the form against downward movement.

In testimony whereof I have hereunto set my hand in the presence of two subscribing witnesses.

PIERRE ZUCCO.
